Fig. 2

Fig. 3

FIG. 1 is a side perspective view of a marine lifesaver radio beacon showing our new design.

FIG. 2 is a side elevational view thereof, the opposite side being identical; and

FIG. 3 is a bottom plan view thereof, the flag being omitted for convenience of illustration.

The cross-hatching on the flag in FIGS. 1 and 2 is partially shown for convenience of illustration. It being understood that the cross-hatching is uniformly continuous over the flag.

We claim:

The ornamental design for a marine lifesaver radio beacon, substantially as shown and described.
